(57) **CLAIM**

The ornamental design for a blood testing device, as shown and described.

DESCRIPTION

FIG. 1 is a perspective top view of a blood testing device with a cover in a closed configuration in accordance with the present invention;

FIG. 2 is a top view of the blood testing device of FIG. 1; FIG. 3 is a left side view of the blood testing device of FIG. 1;

FIG. 4 is a front view of the blood testing device of FIG. 1; FIG. 5 is a right side view of the blood testing device of FIG. 1;

FIG. 6 is a rear view of the blood testing device of FIG. 1; FIG. 7 is a bottom view of the blood testing device of FIG. 1;

FIG. 8 is a perspective bottom view of the blood testing device of FIG. 1;

FIG. 9 is a perspective top view of the blood testing device with the cover in an open configuration in accordance with the present invention;

FIG. 10 is a top view of the blood testing device of FIG. 9; FIG. 11 is a left side view of the blood testing device of FIG. 9;

FIG. 12 is a front view of the blood testing device of FIG. 9;

FIG. 13 is a right side view of the blood testing device of FIG. 9;

FIG. 14 is a rear view of the blood testing device of FIG. 9; FIG. 15 is a bottom view of the blood testing device of FIG. 9; and,

(Continued)

FIG. 16 is a perspective bottom view of the blood testing device of FIG. 9.

The broken lines, the areas within them, and the unshaded areas bounded by both broken lines and solid lines depict portions of the blood testing device that form no part of the claimed design.
